STARCHING MACHINE

George J. Reinitz, Brooklyn, N. Y., assignor to
United Laundry Machinery Corporation, New
York, N. Y., a corporation of New York

Application February 23, 1938, Serial No. 191,928

12 Claims. (Cl. 91—49)

02 The present invention is a new and improved machine for starching laundered articles or parts thereof.

5 The subject-matter hereof consists of improvements in the construction and operation of a machine of the type shown in my prior application, Serial No. 127,638, now matured into Patent No. 2,126,663, issued August 9, 1938.

10 The general object of the invention is the starching of laundered articles or parts thereof in preparation for ironing or pressing. It is adapted particularly for starching the collars, neckbands and cuffs of collar-attached shirts but is equally suitable for starching detached collars 15 and other articles or parts thereof.

Although numerous starching machines have been devised, it is still the general practice, even in large laundries, to starch shirt collars and cuffs and the like by hand dipping, hand wringing of the starched parts and subsequent extracting in a centrifugal machine in preparation 20 for the pressing machines. This method is very slow; hand dipping does not result in an even distribution of starch; it is hard on the worker as the starch solution is in time irritating to the 25 skin; starch spots are produced on the body of the garment during the extracting; and due to uneven distribution of starch it is frequently necessary to rewash some of the garments. 30 When the article is removed from the extractor, into which it has been bundled in a net, it is in a wrinkled condition and must be carefully smoothed when placed in the presser, which slows up the pressing operation.

35 Further objects of the invention are to apply starch evenly and rapidly to a garment or a part thereof and to thoroughly impregnate it with the starch without submerging it in the solution; to remove the excess starch from the garment and conserve it for future use; and to leave the 40 garment in the proper state of dryness and flattened ready for pressing. By eliminating all handling of the articles in the starch, there is no possibility of skin irritation.

45 In commercial laundry practice it is also necessary to meet the demands of the customers by starching clothing, particularly parts of collar-attached shirts, in varying degrees, which we may call light, medium and heavy starching. This is 50 done by using starch solutions of varying concentration. It is therefore a further object of the invention to provide a starching machine which contains supplies of starch of various concentrations and which will enable the operator to change quickly from one starch to another.

Another object is to provide wringing or extracting means which may be adjusted by means of a single screw and which will always exert an even pressure under any adjustment to remove more or less of the solution and leave the garment in a proper state of dryness for pressing. 5

Another object is to provide a starching machine which may easily be cleaned upon completion of its work and which is of simple and rugged construction. The invention provides a 10 machine which can be operated by relatively unskilled labor and to this end it is so arranged that when once adjusted, all the operator has to do is to lay out the parts to be starched upon a moving carrier from which they automatically 15 pass through the starching and extracting means and are delivered preliminarily flattened ready for pressing. Articles come from the machine so well prepared for press work that substantial 20 savings in time in the pressing are effected. 20

Other objects and advantages will become apparent in the course of the following description of the present preferred embodiment of the invention as shown in the drawings in which:

Fig. 1 is a front elevation of a complete machine; 25

Fig. 2 is a rear elevation of the same, part of the rear covering panel being broken away and the gear covering being removed;

Fig. 3 is a plan view of the machine as it would 30 appear when viewed from above, the gear cover being removed;

Fig. 4 is a detailed side view of the starching rolls and related parts as seen from the right of Figs. 1 or 2, certain parts of the frame being in 35 section to expose to view the gears for these rolls;

Fig. 5 is a detailed view of the upper right part of the machine of Fig. 1 showing the starching and extracting rolls, the devices for feeding articles to and through these rolls, and other associated parts. The starch rolls, and other parts, are shown in section, taken on the line 5—5 of Fig. 4, so as to show their interiors;

Fig. 6 is a perspective view of the upper right end of the machine in Fig. 1 as it would appear 45 to one standing to the right and in front of the machine and includes what is shown in Figs. 4 and 5; and

Fig. 7 is a detailed central longitudinal cross-section through the extractor adjustment, the 50 shafts for the extractor rolls and for the starching rolls and part of the upper starch roll carrier, all shown at the left end of Fig. 2.

The machine is constructed to stand on the floor and has a base 10 upon which is mounted 55

a main casting 11, which together carry the working parts of the machine. These working parts consist generally of (1) mechanism for applying and thoroughly working starch into the articles being treated, (2) mechanism for supplying, feeding and circulating starch solution, (3) mechanism for transporting articles being starched, and (4) mechanism for extracting excess starch from the articles. The machine is driven by two electric motors mounted on the base. A reduction gear motor 12, bolted to the side of the base 10, drives the machine proper and another smaller motor is housed in a box 14 in the base for driving the starch-circulating pump 15. Both of these motors are adapted to operate on the usual domestic current supply.

The construction of the apparatus shown in the drawings will now be described in detail. Referring particularly to Figs. 1, 2 and 3, at a convenient height above the floor there is a lower endless belt 16 which runs from one side of the machine to the other, in front of and below the starching mechanism. This belt, which is preferably of heavy rubberized canvas duck, serves to support the parts of garments which are not to be starched, for example the body of a shirt when the collar alone is to be starched. The belt 16 is supported at either end on rollers 17 and 18 which are mounted on shafts 19 and 20 respectively. The belt is driven through shaft 19.

To the rear of and above belt 16 is an upper endless belt 21 similarly supported on rollers 22 and 23 which are carried by shafts 24 and 25 respectively. This belt is driven through shaft 24. The belt 21 serves to carry the article or part thereof which is to be starched into the starching mechanism. It travels at the same linear speed as the belt 16 so that when part of an article is placed on belt 21 the rest of it will be carried along at the same rate on belt 16.

The tension on the belts 16 and 21 may be adjusted and the rollers 18 and 23 aligned by means of the construction shown at the right end of Fig. 2. The main casting 11 is provided with an upstanding end containing the square holes 26 and 27 which receive the square ends of the shafts 20 and 25. Set screws 28, of which there are two on each side of each shaft, are adjusted to effect alignment of the shafts and the proper tension of the belts.

Lying flat on the surface of belt 21 are a plurality of longitudinally-extending stationary parallel wires 29. They are anchored at the right end (Fig. 1) and fastened at the left to a rotatable shaft 30 by which their tension may be adjusted. This shaft is supported in bearing brackets 31, in which it may be fastened by thumb screws 32, and has a knob 33. The wires 29 serve a dual purpose. They prevent wet articles sticking to the belt 21, especially when they reach the end, and they serve as guide lines for the placement of articles on the belt for starching.

The working parts of these elements of the machine are all enclosed by a front panel 34 in the base and the panels 35 and 36 covering the spaces between the upper and lower runs of the belts and their rollers. The vertical guard 37 covers the rear edge of belt 21 and prevents anything from falling to the rear of the machine. The machine is enclosed at the back by the panel 38. The switch 39 is mounted in the front of panel 35 for easy access by the operator and serves for starting and stopping the motors. The panels 35, 36 and 37 are supported on brackets

40 extending outwardly from the main casting 11. Under the central sections of the upper runs of belts 16 and 21 are rigid plates (not shown), supported by the same brackets, which serve to support the belts and prevent them from sagging.

To assure positive delivery of articles to the starching mechanism by the belt 21, a roller 41 is rotatably mounted on an arm 42 freely pivoted on the panel 37 at 43. This roller is preferably made of a heavy metal such as brass and rests on the belt 21 at the point where it travels over roller 22. Roller 41 is grooved so as not to make contact with the wires 29. It may be swung out of operative position and rested on the stop 44. This roller 41 serves to press articles against the belt 21 and thus assures frictional engagement therewith. It also serves as a guard. If the operator leaves his hand on the belt, contact with roller 41 will cause him to withdraw it.

The foregoing constitutes the mechanism for transporting articles to the starch-applying part of the machine which will now be described.

The starch-applying mechanism may be seen in part in Figs. 1, 2 and 3 and is shown in greater detail in Figs. 4, 5 and 6. Referring particularly to Figs. 4 and 5, as the articles leave the end of belt 21 they slide across the wires 29 and enter between two starch-applying rolls which apply starch and thoroughly work it into the material. The upper starch roll 46 is a hollow metal cylinder with closed ends and provided with openings 47 in its cylindrical surface. When in use roll 46 is covered by a tightly fitting, porous, absorbent sleeve 48 of felt or the like, which has been omitted in Fig. 4. The surface of the roll is roughened to prevent slipping of the sleeve. Starch is supplied to the inside of this roll through a pipe 49 which enters through a hollow bearing shaft. The starch passes through the openings 47 and thoroughly wets the sleeve 48 by which it is applied to the upper surface of an article. The shaft for roll 46 is mounted in bearings in a pivoted carrier 50 in the form of a hollow arm. This carrier is mounted on a bushing 51 surrounding the shaft 24 and swings in a vertical plane between the upstanding sides of the casting 11. Located on the shaft for roll 46 inside the carrier 50 is a gear 52 by which the upper starch roll 46 is driven. The combined weight of the arm 50 and the parts carried thereby supply the necessary pressure. A lug 50' carrying a set screw 50", which strikes against the casting 11, makes it possible to adjust the lowermost position of the arm 50 and roll 46.

The rear face of roll 46 is provided with a number of holes 53 through which starch can run out of the roll. They serve a dual purpose. They prevent the building up of any fluid pressure in the roll which would force starch out through the sleeve 48 and they make it possible to empty the roll of starch when changing from one weight to another or when cleaning the machine. Around the shaft behind these holes 53 is a circular splash guard 54 which directs starch flowing out of the holes downward and keeps it off the other parts of the machine.

Vertically below the upper roll 46 is the lower starch roll 56. This roll is made of bronze or other hard material and has an irregular surface, preferably in the form of longitudinal ribs 57. These ribs, in conjunction with the soft cover on the upper roll 46, serve to knead the article passing between the starch rolls in such a manner that the starch is thoroughly worked into the article being starched. The longitudinal

spaces between the ribs also serve to carry starch upwardly and apply it to the under surface of the article. The roll 56 is mounted on a shaft 58 supported in bearings 59 in the casting 11. A drive sprocket 60 is secured on the rear end of shaft 58. Meshing with the drive gear 52 for the upper starch roll 46 is a gear 61, fixed on shaft 58 intermediate the sides of casting 11, from which it can be seen that the power for both starch rolls is derived from sprocket 60 and that they rotate together in opposite directions at the same speed.

To deliver articles between the starch rolls and at the same time prevent their following around the lower roll, a number of small rods 62 are extended between the rolls, being anchored from one end in the guard plate 63 at the end of the belt 21. The lower roll 56 is provided with grooves 64 to receive the rods 62. After starching, articles slide on these rods into the extracting rolls 65 and 66.

The extracting rolls are made of rubber molded on metal sleeves 67 and 68 and are identical in construction so as to be interchangeable. They are removably secured on the shafts 69 and 70 by double-ended slots 71 which engage with pins 72 in the shafts (Fig. 3). This enables the rolls to be locked on their shafts for rotating in either direction.

To produce just the proper degree of dryness to make the starched articles ready for pressing it is necessary to provide means for adjusting the pressure of the extracting rolls. To produce uniform dryness it is also necessary that the rolls be maintained parallel throughout the range of adjustment. These two requirements have been met by the construction shown in detail in Figs. 6 and 7. The lower extracting roll shaft 70 is mounted in fixed bearings in casting 11. The upper extracting roll shaft 69 is mounted in a pair of bearings in the end of a lever arm 73 which is pivoted at about its mid-point on a fixed shaft 74. The pressure adjustment is effected by a hand screw 75 which bears against a cap 76 in the end of a coil spring 77. This spring is held in a retainer 78 bolted to casting 11. By adjusting the tension of the spring, a yielding pressure in any desired amount may be had.

The novel features of the extracting mechanism are not claimed herein as they are the subject of my copending application, Serial No. 243,715.

On the rear ends of the extracting roll shafts 69 and 70 are intermeshing gears 79 and 80 and the drive for these rolls is through a sprocket on shaft 70. The extracting rolls run in opposite directions at the same speed.

To further facilitate positive and automatic delivery of articles from the starching to the extracting rolls and away from the latter, a plurality of endless tapes are provided which cooperate with these rolls in the following manner. The tape 81 passes around the upper starch roll cover 48, between the extracting rolls 65 and 66, out around the guide roll 82 and up over the tension roll 83. Two lower tapes 84 and 85 pass around the lower extractor roll 66 and around a tension-adjusting and guiding roll 86. The rolls 82 and 86 are carried by an arm 87 adjustably secured to casting 11 by a screw 88. The top tension roll 83 is mounted on the end of an eccentric shaft 89 supported in lugs 90 on the top of the carrier 50. The tape 81 is loosened and tightened by revolving the shaft 89. As articles emerge from the extracting rolls 65 and 66 they

are between the upper tape 81 and the two lower tapes 84 and 85, by which positive delivery from the machine is effected.

Referring to Figs. 1 and 3, the lower parts of the starching and extracting mechanism are enclosed by a shield 91, the upper left edge 92 of which is rounded and extends along and slightly above the upper edge of belt 21 for a short distance. This rounded edge 92 functions to lift up the portion of a garment passing over it, elevating it slightly above the belt 21 so as to assure a smooth passage into the starching rolls and to prevent the catching of buttons or parts of the garment in the mechanism through adherence to the belt, as will occasionally happen but for the presence of this device which experience has shown to be of importance.

Referring to Fig. 2, it will now be clear how the various working parts are driven by the motor 12. On the drive shaft 95 are two sprockets 96 and 97 driving the chains 98 and 99 respectively. The chain 98 drives the lower starch roll through sprocket 60 and shaft 58 and the upper belt 21 through sprocket 100 and shaft 24 and is positioned by the idler 101. The chain 99 drives the lower belt 16 through sprocket 102 on shaft 19 and the lower extractor roll through sprocket 80 on shaft 70. The chains, gears and sprockets are normally enclosed by the cover 103 (Fig. 6).

The starch-feeding mechanism and the interchangeable starch supply will now be described. As shown in Figs. 2 and 3, there are four tanks or reservoirs 105a, 105b, 105c and 105d located in the base of the machine. Each tank has an outlet at the bottom connected through a union 106 and a gate valve 107 with the starch feed line 108 leading to the pump 15, which is of the impeller type. Any tank can be quickly removed, even when containing solution, by closing its valve 107 and disconnecting the union 106.

The pump 15 delivers the starch into pipe 109 at the top of which is a T-joint 110 out of which run two branches. The first branch is through the regulating valve 111 and the flexible hose 112 to the pipe 49 feeding the upper starch roll 46. The second branch is through the regulating valve 113 and pipe 114 to a perforated pipe 115 which directs a number of small streams of starch against the lower starch roll 56. At the end of the pipe 115 is an elbow 116 carrying a downwardly discharging open pipe 117. The flow of starch from the pump is therefore as follows: Into the upper starch roll 46 which it leaves through the cover 48 and the holes 53; through the perforated pipe 115 onto the lower starch roll 56; and out the lower open end of pipe 117. All of this starch, except what is actually retained in the articles, runs through the machine and drops into a receiver 118 which extends under the starching and extracting rolls. Across the bottom of the receiver is a screen 119 under which is a return pipe 120 leading to a swing joint 121 to which is connected a swinging pipe 122. This pipe can be positioned over any one of the tanks 105 (a, b, c or d) to return the starch to it.

The operation of the machine is as follows: The parts of the machine are all in the positions shown in the drawings. The starch tanks are filled with starch solutions of different concentrations for light, heavy and medium starching. It is decided which starch is to be used and the appropriate valve 107 is opened fully. The switch is turned on starting the motors, and the starch is circulated by the pump 15. The valves 111 and 113 are adjusted to give the desired amount of

feed to the starch rolls. As the machine runs, the starch solution is being constantly circulated and so is prevented from settling, thus assuring a uniform consistency at all times.

5 The operator then stands before the machine with a supply of damp laundered articles at hand, for example men's collar-attached shirts, taking them one by one and placing the collars on the moving belt 21, using the wires 29 as guides for 10 properly locating them. The body of the shirt is placed on the belt 16. The collar is automatically fed through the starching and extracting rolls and requires no further attention except to receive it as it leaves the machine. Only that 15 part of the article actually passing between the rolls 46 and 56 is starched. As soon as one garment has been placed, it moves to the right and other one can be placed immediately behind it. One operator attending to feeding the machine 20 can easily handle 900 shirts an hour and by increasing the speed slightly a skilled operator can handle 1200 an hour.

To change from one starch to another, the valve 107 from the tank being used is shut off 25 and the machine allowed to run until the starch in circulation has been returned to that tank through pipe 122. When no more starch runs from pipe 122 it is then swung into position to discharge into the next tank selected and the 30 valve for that tank opened. As soon as the starch from that tank has circulated through the machine for a few moments, starching operations may be carried on as before.

To clean the machine after use, all tanks containing starch are shut off, an empty tank is filled 35 with water and its valve opened. The machine is run until all starch has been washed out. The fabric cover 48 on roll 46 is removed and washed in clean water. To remove this cover the tape 81 40 is first loosened by turning the eccentric 89 and is then removed. The carrier 50 for roll 46 can then be swung upwardly on its pivot which gives free access to roll 46 and also to roll 56 and the receiver 118. The extractor rolls 65 and 66 may 45 be removed by loosening screws 75, disengaging the sleeves 67 from pins 72 and pulling the rolls off of their shafts. Tapes 84 and 85 can be loosened by swinging the arm 87 upward.

While the foregoing description of an embodiment of the invention has been given in considerable detail to enable one to practice the invention, it is not intended to limit the invention to such details as many modifications may be made therein within the purview of the invention.

55 What is claimed is:

60 1. A starching machine comprising in combination an upper hollow starching roll having starch outlet openings in its cylindrical surface and further openings in one of its other surfaces for the discharge of surplus starch, an absorbent covering over the said cylindrical surface, means for supplying starch to the inside of said roll, a lower starching roll in contact with the upper roll covering and having a hard irregular generally cylindrical surface, means for supplying starch to the 65 surface of the lower roll, means for rotating the rolls in opposite directions, and means for feeding articles to be starched between the contacting surfaces of said rolls.

65 2. A starching machine comprising in combination a hollow rotating starching roll having starch outlet openings in its cylindrical surface and other openings disposed adjacent the periphery of one of its end surfaces for draining excess starch from the roll, means for supplying

starch to the inside of said roll in excess of the rate of consumption, a tightly fitting cover of yielding absorbent material around said cylindrical surface, a second starching roll rotating in contact with said cover and having an irregular surface coating with said yielding cover to thoroughly knead the starch into fabric passing between said rolls, means for rotating said rolls, and means for delivering articles between said rolls.

10 3. A starching machine comprising in combination a starch supply tank, a hollow upper starching roll having a pervious cover in communication with the interior of said roll and means for discharging excess starch, a lower starching roll rotating in contact with said cover, means for delivering starch from the tank to the inside of the upper roll and to the surface of the lower roll in excess of the rate of consumption, a receiver positioned to receive the excess starch dropping from said starching rolls, and means for returning the excess starch from the receiver to the supply tank for recirculation.

15 4. In a starching machine having a pair of starching rolls adapted to receive and apply starch solution to articles passing therebetween, means for supplying to said rolls starch solutions of various concentrations at the will of the operator, said means comprising a plurality of starch supply tanks each having an outlet, a valve controlling each of said outlets, a conduit in communication with all of said outlets, means for delivering the solution in said conduit to said rolls, and means for returning the unconsumed starch solution to the tank from which it came.

20 5. In a starching machine having a pair of starching rolls adapted to receive and apply starch solution to articles passing therebetween, means for supplying to said rolls starch solutions of various concentrations at the will of the operator, said means comprising a plurality of starch supply tanks for holding said solutions, means including a pump for delivering the contents of a pre-selected tank to said rolls at a rate in 25 excess of the normal starch consumption, a receiver for the excess starch, and means for returning the starch from the receiver to a pre-selected one of said tanks, whereby the solution being used for starching is continuously circulated.

25 6. In a starching machine having an upper hollow starching roll provided with discharge openings, and a lower starching roll adapted for receiving starch externally, means for supplying to said rolls one of several concentrations of starch solution, said means comprising a plurality of starch supply tanks for holding said solutions, a conduit in communication with all of said tanks, means including a valve connecting each tank with said conduit, a pump for receiving starch from said conduit, means for directing starch from the pump to the interior of the upper starching roll in excess of the amount consumed, means including an open conduit for 30 directing starch to the lower starching roll in excess of the amount consumed, a receiver below said rolls and said extracting means into which the unconsumed starch falls, and a second conduit from the outlet of said receiver adapted for 35 selective positioning to return the unconsumed starch to any one of said tanks, whereby the contents of any tank can be continuously circulated through the machine.

7. A machine for starching only a part of a

garment comprising, in combination, a pair of starch receiving and applying rolls, a moving endless belt adapted to receive the part of the garment to be starched and feed it between the rolls, and a plurality of stationary wires extending longitudinally of the belt adjacent to its surface and beyond the end of the belt nearest to said rolls upon which the said garment part slides with the movement of the belt, said wires serving to prevent adherence of the garment to the belt and directing it away from the discharge end of the belt toward said rolls.

8. A machine for starching only a part of a garment comprising, in combination, a pair of starch receiving and applying rolls, a first moving endless belt adapted to receive the part of the garment to be starched and feed it between the rolls, a second moving endless belt adjacent the first belt and running parallel thereto for carrying the rest of the garment, a roller supported on a pivoted arm so as to bear against the discharge end of the first belt nearest to said rolls and assure frictional contact between that belt and the garment part thereon, and a member having a smoothly rounded edge extending along and slightly above the discharge end of the first belt whereby part of the garment is lifted slightly away from the first belt as the adjacent part passes under said roller.

30 9. In a starching machine wherein the starch is applied by passing the article to be starched between a pair of oppositely revolving contacting rolls, means for applying starch to the surface of said article comprising, as one of said pair, a hollow cylindrical roll having outlet openings in its cylindrical surface, an absorbent covering over said cylindrical surface adapted to receive starch through said openings and apply it to said article, means for directing starch to the inside of said roll, said roll having further openings in one of its other surfaces for the discharge of excess starch, whereby the roll may be

charged with starch at a rate in excess of consumption without building up internal pressure.

10. In a starching machine having starch applying mechanism adapted to receive and apply starch, means for supplying to said mechanism starch solutions of various concentrations comprising reservoirs for a plurality of starch solutions, a pump, means for selectively connecting the pump with a preselected reservoir, means for delivering the starch solution from the pump to 10 said mechanism at a rate in excess of consumption, a receiver for excess starch flowing from said mechanism, and means for returning said excess to the reservoir from which it came.

11. In a starching machine having starch applying mechanism adapted to receive and apply starch, means for supplying to said mechanism starch solutions of various concentrations comprising reservoirs for a plurality of starch solutions, conduit means adapted for selective connection with one of said reservoirs for delivering starch to said mechanism, a receiver for excess starch flowing from said mechanism, means for selectively returning said excess to one of said reservoirs, and a pump for circulating the 25 starch.

12. In a machine for delivering a part of a limp fabric article into mechanism adapted to grasp said part, said machine including a pair of endless belts travelling in parallel relationship 30 one at a greater elevation than the other and cooperating to transport said article, means for assuring delivery of the article from the end of the upper belt comprising a roller pressed toward the upper belt adjacent its discharge end 35 to assure frictional engagement of the article with the belt, and a member having a smoothly rounded surface extending along and slightly above and beyond the discharge end of the upper belt adjacent said roller, whereby said article 40 is lifted slightly away from the upper belt as it approaches the discharge end.

GEORGE J. REINITZ.
